O. M. SHECK.
ADJUSTABLE LAMP CARRIAGE DEVICE.
APPLICATION FILED JULY 7, 1917.

1,257,131.

Patented Feb. 19, 1918.

2 SHEETS—SHEET 2.

UNITED STATES PATENT OFFICE.

OSCAR M. SHECK, OF CLEVELAND, OHIO, ASSIGNOR TO THE ARGUS LAMP AND APPLIANCE COMPANY, OF CLEVELAND, OHIO.

ADJUSTABLE LAMP-CARRIAGE DEVICE.

1,257,131.

Specification of Letters Patent. Patented Feb. 19, 1918.

Application filed July 7, 1917. Serial No. 179,276.

To all whom it may concern:

Be it known that I, OSCAR M. SHECK, a citizen of the United States, residing at Cleveland, in the county of Cuyahoga and State of Ohio, have invented certain new and useful Improvements in Adjustable Lamp-Carriage Devices, of which the following is a specification.

This invention relates to devices for supporting or mounting electric lamps in housings provided therefor and that are employed in connection with motion picture apparatus, stereopticons and certain stage lighting apparatus. In a prior application of mine bearing filing date the 16th of April, 1917, and Serial No. 162,464, I have described and claimed a device of this character, and the present invention has reference to specific improvements which simplify the construction and operation with substantially the same objects in view, namely the provision of a lamp carriage that is universally adjustable and self contained, thereby making it adaptable for placement and operation in lamp houses of any of the types in common use and that are already installed. Another object of the invention is to provide a simple, economical and efficient construction embodying a suitably insulated contact member to which the lamp socket is attached, the said member being adjustably and detachably connected with the carriage that is universally adjustable, and that is mounted on a bracket independent of but adaptable to adjustable application in existing types of lamp houses. A prominent feature of the present invention is the means provided for vertical adjustment whereby the lamp carriage may be readily and quickly elevated a sufficient distance to allow the lamp socket mounting to be freely removed through the door opening of the lamp house, this and the other features will hereinafter be described, and with the above and other apparent objects in view the invention consists in the construction, arrangement and combination of the parts as described, and pointed out definitely in the claims, reference being had to the accompanying drawings which are made a part of the specification and in which similar characters are employed to designate similar parts.

In the said drawings Figure 1 is a side elevation of the improved device. 55

Fig. 2 is a plan view.

Fig. 3 is a longitudinal central section of the device with the lamp socket in elevation and the upper portion broken away.

Fig. 4 is a transverse section through the reflector and its supporting member. 60

Fig. 5 is a front elevation of the improved device.

Figs. 6 and 7 are rear end, and side elevation, respectively of a modified form of construction, and Fig. 8 illustrates a horizontal adjusting means, on an enlarged scale. 65

As above stated the present invention is an improvement on my former lamp carriage, and certain parts of the construction are substantially the same. The main supporting bracket 1 on which the operative parts are mounted is similar in form, being made of sheet metal and provided with vertical end members 1^a and 1^b connected by longitudinal tie rods 2. Mounted on the tie rods 2 is a slidable cross bar 3 provided with bearing sleeves 3^a. Two vertical rods 4 are attached to the cross bar 3, and mounted on these vertical rods is a cross-head 5 provided with vertical bearing sleeves 5^a. The lamp carriage bracket 6 is firmly attached to the cross-head 5 and is therefore movable therewith. The bracket 6 has attached thereto contact ways 7 and 7^a, being insulated from said bracket by the members 8. The lamp socket 9 is attached to the insulated block 10 which carries the metallic members 11 and 11^a, said members bearing on the inclined faces of the ways 7 and 7^a and held in contact therewith by the spring members 12 and 12^a. A buttress member 13 is attached to the bracket 6 and provides an abutment for the screw 14. The screw 14 is threaded in the block 10 and operates conjointly with the buttress 13 to provide transverse adjustment for the lamp which is inserted in the socket 9, said socket being seated on the block 10. Electric operative connections are provided from the lamp socket to the members 7 100 and 7^a.

The construction thus far described is similar to that of my former application above referred to, and I will now describe the construction and arrangement of the elements that are new but which cooperate 105

with the other parts to produce the desired efficiency.

An inclined guide member 15 is attached to the base of the bracket 1 at 15^a and also to the 5 vertical bracket member 1^b at 15^b in a medial line of said bracket 1. The members 3, 5, and 6 are provided with clearance slots to accommodate the guide 15, as best shown in Fig. 3, and in the embodiment as shown a 10 guide plate 16 is attached to the cross-head 5 and has a bearing on both the upper and lower faces of the member 15. An operating rod 17 is firmly attached to the cross bar 3 and extends longitudinally and medially a 15 through the vertical bracket member 1^b, being free to longitudinally move therethrough. It will be seen that when the bar 3 is moved in the direction of arrow Fig. 3, said bar being actuated by the rod 17, a vertical movement a 20 is imparted to the cross-head 5 owing to its mounting on the vertical members 4 and its bearing on the inclined guide 15. A result of this combined movement is shown by dotted lines in Fig. 1. The reverse or a 25 forward movement of rod 17 causes the cross-head 5 to travel downward on the vertical rods 4, due to the bearing of member 16 on the under side of guide member 15, and said downward movement is limited by a 30 the contact of member 5 with member 3. The lamp carriage being supported on the cross-head 5 travels with said cross-head.

An alternative or modified construction is illustrated in Figs. 6 and 7, wherein spiral 35 springs 20 are mounted on the vertical members 4, said springs being confined under compressed tension between the cross-head 5 and a cross member 21. In this construction the springs 20 are compressed by the a 40 upward movement of member 5, and the expansive force of said springs carries the member 5 downward on the incline 15 when the member 3 is pushed forward.

The cross member 21 is mounted on the 45 members 4 and is vertically adjustable thereon, a set screw 22 being provided for fixing said cross member in the desired position. A socket 23 is attached to the cross member 21 and provides a suitable a 50 receptacle for the reflector 24. The reflector socket may be permanently attached to member 21, but it is preferably made adjustable as shown, to provide for focusing to meet irregularities in lamp construction.

55 Provision is made for longitudinal adjustment of the entire structure above described relative to the lamp house, and to this end the tie rods 2 are extended a predetermined distance outside the bracket 1 a 60 and have threaded on their terminals spear head members 25 adapted to point bearings in buttresses 26. The members 26 may be the walls of the lamp house or they may be auxiliary vertical plates attached to the a 65 floor of the house. It will be seen that the

threaded connection of the spear heads 25 co-acting with the point bearings provides the desired longitudinal adjustment of the main bracket 1. For convenience in this operation I prefer a right and left hand thread, respectively on the tie rod terminals, as shown in Fig. 8, although this is not an imperative construction as will readily be understood. It will also be understood that there may be changes in the details of construction without departure from the spirit of the invention or the scope of the claims. 75

What I claim and desire to secure by Letters Patent is.

1. In a device for the purpose set forth, 80 the combination of a supporting member slidably mounted on fixed horizontal guides; vertical guide members attached to said supporting member; a lamp carriage support slidably mounted on said vertical guides; 85 an inclined guide member on which said carriage support is seated, the relative arrangement of the inclined guide and the vertical guides being such that horizontal movement of the first named supporting member will 90 cause a vertical movement of the carriage support through its bearing on the inclined guide.

2. An adjustable lamp carriage support comprising a main supporting bracket, a 95 horizontally slidable frame mounted in said bracket on fixed guides connected therewith, vertical guides attached to said slidable frame, a lamp supporting bracket slidably mounted on said vertical guides, an inclined 100 guide member on which said lamp supporting bracket bears, attached to the main bracket, and means for actuating the horizontally slidable frame thereby imparting a vertical movement to the lamp carriage support through its bearing on the inclined guide. 105

3. An adjustable lamp carriage support, comprising a main supporting bracket, a horizontally slidable frame mounted in said 110 bracket on fixed guides connected therewith, vertical guides attached to said slidable frame, a lamp supporting bracket slidably mounted on said vertical guides, an inclined guide member on which said lamp supporting bracket is seated, means for retaining said lamp supporting bracket so seated, and means for actuating the horizontally slidable frame thereby imparting a vertical movement to the lamp carriage support through 115 its bearing on the inclined guide. 120

4. In a device for the purpose set forth, the combination of a main supporting bracket; a horizontally slidable frame mounted in said bracket on fixed guides 125 which form a part of said bracket; vertical guides attached to said slidable frame; a reflector member mounted on said vertical guides; a lamp supporting bracket slidably mounted on said vertical guides; an inclined 130

guide member on which said lamp supporting bracket is seated; means for retaining said lamp supporting bracket so seated; and means for actuating the horizontally slidable frame.

5. In a device for the purpose set forth, the combination of a main supporting bracket; a horizontally slidable frame mounted in said bracket on fixed guides 10 which form a part of said bracket; vertical guides attached to said slidable frame; a reflector member mounted on said vertical guides; a lamp supporting bracket slidably mounted on said vertical guides; an adjustable lamp socket mounted on said bracket; an inclined guide member on which said lamp supporting bracket is seated; means 15 for retaining said lamp supporting bracket so seated; and means for actuating the horizontally slidable frame.

6. In an adjustable lamp carriage support, the combination of a main supporting bracket; guide rods attached to and extending longitudinally through said bracket; adjusting members threaded on the terminals 25 of said rods; buttresses on which said ad-

justing members bear; a lamp supporting carriage mounted on said guide rods; and means for vertically and horizontally adjusting said carriage relative to the main 30 supporting bracket.

7. In an adjustable lamp carriage support, the combination of a main supporting bracket; guide rods attached to and extending longitudinally through said bracket; adjusting members threaded on the terminals 35 of said rods; buttresses on which said adjusting members bear; a bracket member slidably mounted on said longitudinal guide rods; vertical guide members attached to 40 said slidable bracket; a lamp carriage support slidably mounted on said vertical guides; an inclined guide member on which said carriage support is seated; and means for actuating the horizontally slidable 45 bracket thereby imparting a vertical movement to the lamp carriage support through its bearing on the inclined guide.

In testimony whereof I affix my signature.
OSCAR M. SHECK.

Witness:

FRANK R. BLAKESLEE.
